UNITED STATES PATENT OFFICE.

JOSEPH SARGENT, OF WAUSAU, WISCONSIN.

COLLAR BUTTON.

Application filed July 3, 1928. Serial No. 290,066.

This invention relates to a new and improved type of collar button and has for its primary object the provision of a collar button in which the stem thereof is movable 5 relative to the back or base so that when any lateral strain is placed upon the stem, the same will give, leaving the base portion flat against the neck of the wearer.

With the present collar button, wherein 10 the stem is rigid with the base, the base is frequently caused to dig or cut into the neck when any pull is exerted upon the stem, thus causing extreme uncomfortableness. With 15 the present button, this unpleasant feature is avoided in the manner above described, that is, by allowing the stem to swing relative to the base, leaving the base in position flat against the neck.

The invention will be best understood 20 from a consideration of the following detailed description taken in connection with the accompanying drawing forming part of this specification, with the understanding, however, that the invention is not confined to 25 any strict conformity with the showing of the drawings but may be changed or modified so long as such changes or modifications mark no material departure from the salient features of the invention as expressed in the 30 appended claim.

In the drawings:—

Figure 1 is a view in side elevation of the collar button embodying the present invention, the same being shown in position, in a 35 collar band;

Figure 2 is a transverse sectional view through the base of the button, showing the connection between the base and the stem;

Figure 3 is a sectional view taken through 40 the button stem above and looking toward the base.

Referring to the drawing in detail, the numeral 1 indicates the base portion of the present improved button, which portion is of

the usual disk shape and is preferably 45 formed of a single thickness of thin material such as silver or aluminum. At the central portion of the base, there is formed the upstanding stud 2 which is hollow as indicated at 3 and has an opening 4 through the top 50 thereof communicating with the hollow interior.

The stem of the button is indicated as a whole by the numeral 5. The shank portion 6 of the stem carries the head 7 upon one 55 end and a ball 8 upon the other end. The ball 8 of the stem is snugly positioned within the socket 3, the shank 6 extending through the opening 4 as shown in Figure 2. Some play is allowed between the edge of the opening 4 and the shank 6 of the stem, thus permitting free movement of the stem upon its base.

The stud 2 projects into the button holes 9 of the collar band, which is shown in section and indicated by the numeral 10. It will be readily seen that when the present button is in use, any pull of the collar upon the stem 5 will cause the stem to swing upon the base 1 and thus relieve the strain without 70 twisting the base and forcing the edge thereof into the neck of the wearer.

Having described my invention what I claim is:—

A collar button of the character described, 75 comprising a base having a flat top surface, a hollow stud formed centrally of the base upon the top face thereof, said stud being of the same width throughout its length and opening through the outer end thereof, a 80 stem, and a ball formed upon one end of the stem and inclosed in said hollow stud with said stem extending through the open end of the stud, and acting to permit free movement of the stem upon the base. 85

In testimony whereof I hereunto affix my signature.

JOSEPH SARGENT.
